ABSTRACT OF THE DISCLOSURE

A method of manufacturing a curved sealing element for use in the side of the lobed rotor of a rotary piston internal combustion engine in which a straight strip of material of the required cross-sectional shape is first produced and is subsequently formed whilst hot to the required configuration in which it is adapted to be located in a curved groove formed in the rotor side.

This invention relates to rotary piston internal combustion engines of the kind in which a lobed rotor rotates in a chamber formed in a housing. It is necessary to form a seal between the sides of the rotor and the housing and one object of the present invention is to provide an improved method of making a sealing element for use in this way.

In accordance with the invention a method of making a curved sealing element for use with the lobed rotor of a rotary piston internal combustion engine comprises producing a ferrous casting which is subsequently cut into strips to provide a plurality of blanks, machining each of said blanks to the required cross-sectional shape, placing each blank in a jig to bend it to a curved configuration of open form and then heating the jig and blank to set the blank in said curved configuration.

The invention will now be more particularly described with reference to the accompanying drawing in which—

FIGURES 1 and 2 are perspective views illustrating alternative steps in carrying out examples of a method of making a sealing element in accordance with the invention and

FIGURES 3 and 4 are respectively a side view and a cross-section on the lines 4—4 of FIGURE 3 of a jig which can be used in carrying out said method.

In one example of a method in accordance with the present invention ferrous material of a suitable composition is cast into a flat slab 10 as shown in FIGURE 1 which is then cut in any convenient manner so as to form a plurality of straight strips of elongated configuration, the cuts being indicated by dotted lines 11. Each strip thus formed is then machined whilst straight and in any convenient manner to the required cross-sectional configuration and is afterwards formed whilst hot to a curved configuration so that the curved strip is adapted to engage in a correspondingly curved slot or groove formed in the side of a lobed rotor of a rotary piston internal combustion engine.

In forming a straight strip into the required curved configuration the strip is bent to the required shape in any convenient form of jig and is then placed in a furnace or oven which may have a neutral atmosphere. Such a jig may take the form shown in FIGURES 3 and 4, the jig comprising an inner circular ring 12 together with a pair of arcuate clamping members 13 which can be detachably connected to the ring 12 by bolts 14. Thus two sealing elements (indicated by reference numeral 15) can be clamped in the jig between the ring 12 and the members 13 before the jig is inserted into the furnace or oven.

2

As an alternative to casting the ferrous material into a flat slab 10, as above described, the material may be centrifugally cast into the form of a hollow cylinder 16 (as shown in FIGURE 2) which is subsequently divided by a plurality of slits 17 each extending parallel to the axis of the cylinder so as again to provide a plurality of straight strips of metal which are then machined to the required cross-sectional shape, before being clamped in a jig and subsequently formed to a curved configuration in a furnace or oven.

In use, a sealing element formed as above described may form part of a multi-element sealing system which provides a seal between the lobed rotor of a rotary piston engine and the associated housing in which said rotor rotates. Thus for example where the rotor is of generally triangular configuration the sealing system would include straight sealing strips fitted in grooves cut in the apices of the rotor, said sealing strips mating with corner bolts housed in blind holes also formed in the apices of the rotor, and also curved sealing elements formed as above described in accordance with the present invention, there being provided at least one curved sealing element between each pair of adjacent corner bolts on each side of the rotor. Hitherto such curved side seals have been made by machining them from cast iron rings and although this method of manufacture is satisfactory for use on small engines, for larger engines it does not result in economical manufacture. This is because firstly it is necessary to machine the seal blank to the form of a short length of very thin walled large diameter tube in order to reduce the weight of the seal as much as possible and secondly the centrifugally cast cylinder providing the blank from which the rings are machined must be provided with an excessively large machining allowance. With the present invention as above described any machining is very readily effected whilst the sealing strip is in a straight condition and after the strip has been heat formed to the required curvature no further machining is necessary with the possible exception of reducing the length of the strip to provide the correct working clearance in use.

Having thus described my invention what I claim as new and desire to secure by Letters Patent is:

1. A method of making a curved sealing element for use with the lobed rotor of a rotary piston internal combustion engine, said method comprising producing a ferrous casting which is subsequently cut into strips to provide a plurality of blanks, machining each of said blanks to the required cross-sectional shape, placing each blank in a jig to bend it to a curved configuration of open form and then heating the jig and blank to set the blank in said curved configuration.

2. A method as claimed in claim 1 wherein the ferrous casting is in the form of a flat slab.

3. A method as claimed in claim 1 wherein the ferrous casting is in the form of a hollow cylinder, a plurality of blanks being formed by slitting said hollow cylinder along lines parallel to its axis.
